DEPTH GAUGE

Charles H. Allen and Rosslyn C. Allen,
Pittsburgh, Pa.

Application July 29, 1938, Serial No. 222,011

3 Claims. (Cl. 33—199)

This invention relates to a gauge, and while primarily designed and intended for ascertaining and indicating variations in the depths, from required standards, of internal screw threads, in 5 sleeve couplings for pipes and the like, it will be obvious that the device may be employed for any other purposes wherein it is found to be applicable.

Important objects and advantages of the invention are to provide an appliance of the character described, which is operable for accurately and quickly measuring and indicating variations from the proper depths of internally disposed screw threads, which may be readily and 15 conveniently engaged on the product to be measured or removed from the latter, which is simple in its construction and arrangement, positive in its action, attractive in appearance, durable and efficient in its use, and economical in its 20 manufacture.

With the foregoing and other objects in view which will appear as the description proceeds, the invention resides in the novel construction, combination and arrangement of parts therein specifically described and illustrated in the accompanying drawing, but it is to be understood that the latter is merely illustrative of an embodiment of the invention, and that the actual needs of practice and manufacture may require 30 certain mechanical variations from the embodiment shown. It is, therefore, not intended to limit the invention to the disclosure thereof illustrated, but rather to define such limitations to the scope of the claims hereunto appended.

35 In the drawing wherein like numerals of reference designate corresponding parts throughout the several views:

40 Figures 1 and 2 are, respectively, side elevation and top plan views of a depth gauge constructed in accordance with the invention.

Figure 3 is a longitudinal cross sectional view of the barrel and of associated parts.

Figure 4 is a top plan view of the balance beam.

45 Figure 5 is a rear end view of the clamping arm and of attached bell crank lever.

Figure 6 is a front end view of the gauge applied to the work to be measured.

50 Figure 7 is an enlarged side view of the seating plate, and Figure 8 is an enlarged fragmentary side view of the balance beam and of its fulcrum suspension elements.

55 Referring in detail 1 denotes an elongated, tubular and cylindrical body or barrel, which is disposed horizontally and has its respective ends closed by a pair of closure plugs 2.

An elongated balance beam 3 is mounted in the barrel 1, and has an accurately equi-poised fulcrum suspension in the latter, allowing the beam to alternately move up and down in a limited see-saw movement. The fulcrum suspension or axis of the beam comprises a sphere or ball 4 which is shiftably mounted in an aperture provided therefor in said beam centrally of the ends of the latter. The ball is provided with a transversely extending bore 5, which latter is formed with a corresponding disposed, triangularly-shaped groove 6 in the top wall thereof. A fulcrum pin 7 is removably and transversely fixed, as at 8, in the barrel and extends through the bore of the ball. The fulcrum pin has a knife-edge top edge 9 seating in the apex of the triangularly-shaped bore groove 6. The bottom of the ball 4 is provided with a groove 10 extending parallel to the bore groove 6. A set screw 11 is adjustably mounted in the beam 3 and engages in the ball groove 10. The set screw maintains the ball 4 in the beam in a position disposing the apex of the groove 6 upwardly at all times, but otherwise allows the automatic adjustment of said ball in the beam to an extent, whereby the 15 top edge 9 of the fulcrum pin 7 will accurately seat in the apex of the bore groove 6 throughout the length thereof. This fulcrum suspension of the beam 3 provides an axis for the latter with only a minimum of friction. 20

The balance beam 3 has its bottom face tapered from its center toward respective ends thereof to conserve weight, and has a forked front end 12 which is beveled to provide comparatively sharp top edges 13. The top rear portion 14, of the 25 balance beam, is flat and recessed to dispose same below the plane of the top of said beam. 30

An anvil 15, having tapered sides and a rounded top 16 extending parallel to the longitudinal disposition of the barrel 1, is secured to the top 40 of the latter at the front end thereof. The anvil is provided with a vertical passage 17, communicating with the interior of the barrel, for receiving a vertically disposed plunger 18. The upper end of the latter carries a tip 19, which is pointed, and has a fixed, detachable connection with said plunger, and projects through the top of the passage 17. 45

The plunger 18 projects through the forked front end 12 of the balance beam 3, and is carried by a cross-pin 20, which is fixed in said plunger and seats upon the sharp top edges 13 of said forked front end. The plunger is vertically shiftable and free of friction in the anvil passage 17, and is held against rotation in the 50 55

- latter by a pin 21 fixed in the plunger and projecting rearwardly in the forked beam end 12. The lower end of the plunger 18 has a frictionless engagement in a socket bearing 22 fixed in the bottom of the barrel 1.
- 5 A dial indicator 23, of any suitable conventional construction, is mounted on a support 24, which latter is fixed to the top of the barrel 1 at the rear end thereof. The indicator is provided with a scale graduated dial, each graduation representing one one-thousandth of an inch, and includes a spring controlled actuating rod 25. The latter extends vertically through a passage provided therefor in the support 24 and projects 10 into the barrel and has its lower end seated upon the flat, recessed rear end 14 of the balance beam 3. The normal action of the spring controlled actuating rod 25 will shift the balance beam 3 to move the plunger 18 vertically upward in the 15 anvil passage 17. The depression of the plunger, however, will shift the balance beam to move the actuating rod upwardly whereby the indicator is operated to indicate, upon the dial of the indicator the extent of such depression of the plunger.
- 20 A clamping arm 26 is provided for properly engaging the product or work to be measured. The rear end of the clamping arm is detachably fixed to the top of the upwardly disposed connecting member 27 of a bell crank lever 28 by means of a bolt 29 having a knurled head 30. The bell crank lever is pivotally connected by a pivot pin 31 in a bearing bracket 32, which latter is fixed on the top of the barrel 1 adjacent to the indicator 23.
- 25 The clamping arm 26 is of considerable length and extends forwardly to the anvil 15 above the barrel 1 from its connection with the bell crank lever 28. The front free end of the clamping arm is provided with an integrally formed cross-head 33. The latter has a longitudinal concavely curved bottom face 34, which is provided with an aperture 35 for normally receiving and protecting the pointed plunger tip 19 when the instrument is not in use.
- 30 The bell crank lever 28 includes a rearwardly disposed depression member 36 adapted to be engaged and depressed by the thumb of the operator for elevating or spacing the cross-head 32 from the anvil 15 when the product to be measured is to be placed between said cross-head and anvil. A spring 37 is mounted on the bearing bracket 32 and engages the depression member 36, of the bell crank lever. The normal action of the spring 37 actuates the bell crank lever 35 to force the cross-head 33 toward the anvil 15. The cross-head 33 cannot actually contact with the anvil 15, as the movement of the bell crank lever, to lower said cross-head, is limited by the engagement of the toe 45, of the bell crank lever, 40 with the bearing bracket 32, as shown in Figure 1.
- To assure the proper alignment of the connection of the clamping arm 26, with the bell crank member 27, the top face of the latter is provided with a triangularly shaped rib 38 which is engaged by a correspondingly shaped groove 39 formed in the bottom face of the clamping arm at the rear end of the latter.
- 45 A seating plate 40, suitably apertured for the passage of the bolt 29, is mounted between the head 30 of the latter and the top face of the clamping arm 26. The seating plate carries a pair of fixed, depending guide pins 41, which extend into pockets provided therefor in the top of the clamping arm. Each of the guide pins is 50 surrounded by a spring 42, which are mounted

in respective pockets and which normally function to force the seating plate upwardly toward the bolt head 30.

The function of the seating plate 40 is to resiliently sustain the clamping arm 26, when the bolt 29 is partially released from its engagement in the lever member 27. When the bolt 29 is so released the clamping arm may be lifted against the action of the springs 42 to cause the arm groove 39 to clear the rib 38, and thereby allow 5 the clamping arm to be swung laterally to shift the cross-head 33 from above the anvil 15 to provide the necessary clearance for calibrating the instrument or for any other purposes required. Further, when returning the clamping arm to its normal, operative position, the action of the seating plate 40 and springs 42 will provide a clicking reengagement of the rib 38 in the arm groove 39 and thereby facilitate the proper adjustment of the clamping arm.

The adaptation of the gauge is illustrated in Figure 6, as applied to a pipe coupling 43, formed with the usual internal screw threads 44. The wall of the coupling is positioned between the anvil 15 and the cross-head 33, with the latter 25 disposed outwardly against the outer surface of the coupling and with the anvil disposed inwardly against the screw threads of the coupling. The concaved bottom face 34, of the cross-head, 30 conforms to the engaged curvature of the coupling and snugly seats upon the latter. Such engagement of the coupling will be maintained by the resilient action imparted to the clamping arm 26 by the spring 37. The plunger tip 19 enters a depression between a pair of adjacent 35 convolutions of the screw thread, and if the said depression is precisely of the proper depth, the balance beam 3 will be actuated to operate the indicator to register zero, thereby showing that the screw thread is of the proper depth. However, should the screw threads be too deep or too shallow the balance beam will be actuated to operate the indicator to register the variation of the thread screw depth from the proper depth.

The indicator 23 is so calibrated that when a 45 screw thread of proper depth is placed on the anvil 15 and engaged by the plunger tip 19, in the manner stated, the balance beam 3 will be actuated to operate the indicator to register "zero," and variations from the proper depth 50 will be registered, respectively as minus or plus from "zero" as such variation may be, by graduation representing one one-thousandth of an inch.

The present invention provides a most efficient 55 instrument of its kind, which may be readily employed by a person of ordinary skill, for precisely measuring screw thread depth variations, even if the latter be so infinitesimal as to be incalculable by any other device used for analogous purposes.

60 What we claim is:

1. A depth gauge for internally disposed screw threads comprising a horizontally disposed tubular body, a balance beam pivotally connected intermediate of its ends in said body, an anvil provided with a vertically extending passage mounted on the top at the front end of said body, a plunger having a pointed tip mounted and vertically shiftable in said passage and supported on the front end of said beam, and an indicator element mounted on the top at the rear end of said body and engaged by the rear end of said beam and actuated by the movement of the latter for indicating the extent of the movement of said plunger, a clamping arm pivotally supported by 65

said body, and means tending to force said arm toward said anvil.

2. A depth gauge for internally disposed screw threads comprising a horizontally disposed tubular body, a balance beam pivotally connected intermediate of its ends in said body, an anvil provided with a vertically extending passage mounted on the top at the front end of said body, a plunger having a pointed tip mounted and vertically shiftable in said passage and supported on the front end of said beam, and an indicator element mounted on the top at the rear end of said body and engaged by the rear end of said beam and actuated by the movement of the latter for indicating the extent of the movement of said plunger, a clamping arm pivotally supported by said body, and spring controlled means carried by said body normally tending to force the free end of said arm toward said anvil.

20 3. A depth gauge for internally disposed screw

threads comprising a horizontally disposed tubular body, a balance beam pivotally connected intermediate of its ends in said body, an anvil provided with a vertically extending passage mounted on the top at the front end of said body, a plunger having a pointed tip mounted and vertically shiftable in said passage and supported on the front end of said beam, an indicator element mounted on the top at the rear end of said body and engaged by the rear end of said beam and actuated by the movement of the latter for indicating the extent of the movement of said plunger, a bearing bracket fixed on said body, a bell crank lever pivotally supported by said bracket, a clamping arm having one end thereof fixed to said lever, and a spring engaging said body and said lever and normally tending to force the free end of said arm toward said anvil.
